UNITED STATES PATENT OFFICE.

EFFINGER E. WHIPPLE, OF EATON RAPIDS, MICHIGAN.

HARROW.

SPECIFICATION forming part of Letters Patent No. 392,654, dated November 13, 1889.

Application filed March 15, 1888. Serial No. 267,245. (No model.)

To all whom it may concern:

Be it known that I, EFFINGER E. WHIPPLE, a citizen of the United States, residing at the City of Eaton Rapids, in the county of Eaton 5 and State of Michigan, have invented new and useful Improvements in Harrows, of which the following is a specification.

My invention relates to improvements in harrows in which the teeth are fastened to arched beams bolted to a front and rear sill; and the objects of my improvements are to provide a cheap, durable, and elastic harrow and to facilitate the cultivation of the ground with a harrow so constructed as to combine at 15 once the benefits of a roller, leveler, and harrow. I attain these objects by the mechanism illustrated in the accompanying drawings, in which—

Figure 1 is a detail view in perspective of 20 the entire harrow ready for operation. Fig. 2 is the beam with a tooth attached. Fig. 3 is the sill; Fig. 4, the beam; Fig. 5, the beam and sill; Fig. 6, a tooth; Fig. 7, the evener; Fig. 8, an end view of the harrow; Fig. 9, a like 25 view of the harrow; Fig. 10, the beam and sills; Fig. 11, an end view of one of the beams.

Similar letters refer to similar parts throughout the several views.

The sills A A A A and beams B B B consti- 30 tute the frame work of my improved harrow.

The harrow is made in one or more sections, and can be connected in the center by hinges; or, if preferred, swivel joints or rings and hooks may be used. The beam B is constructed 35 of spring-steel crowning in the center, with the ends b b straightened, as shown in Fig. 4. In each of the ends b b of the beam B are drilled two holes, and in the back of the beam B are drilled the two holes c c near the shoulders of 40 the beam B. I do not wish to be confined, however, to the entire beam being constructed of metal or in a continuous piece, since the entire piece or back can be constructed of wood and the sloping sides r s can be attached 45 thereto, as shown in Fig. 9. The foot b b of the beam B can also be dispensed with by drilling holes m n o in the sloping sides r s, Fig. 11.

The sill A is of convenient length for a section of the harrow, and can be constructed 50 either of wood or iron, through which holes x x x are bored or drilled at the desired dis-

tance apart intended for the beams B B B. If it is intended for the sections of the harrow not to run parallel to each other, the inner ends, i i, of the sill A A in Fig. 3 will be 55 cut mitering. Otherwise the ends i i can be made square.

For the purpose of disclosing to others unskilled in the art the manner of constructing and operating my device, I bolt the teeth a a a to the crowning part of the beams B B B at c c, each alternate tooth turning in an opposite direction. Any number of teeth can be attached to the crowning part of the beam B by increasing the distance between 65 the sloping sides r s. By having the sloping sides r s constructed of steel and by using spring-steel teeth a a a an elasticity is given to the harrow especially adapted to rough, uneven, or stony ground, although any style of teeth 70 desired can be used. I now bolt the sills A A to the beams B B B by means of bolts passing through the ends b b of the beam B and the sills A A, or, if desired, the sills A A can be bolted to the sloping sides r s, Fig. 11. The 75 sills A A can be bolted onto the sloping sides r s at any desired distance from the ends b b by having the holes m n o drilled at the place desired. The sills A A can be bolted on the top of the ends b b or underneath or on the top 80 or under side of the sloping sides r s.

In all instances it is not necessary to use both of the sloping sides r s and both the forward and rear sills A A, as the forward sill A, when not needed as a leveler, may be dispensed 85 with by attaching the forward ends of the beams B B B to a rod or sill for the purpose of connecting the draft, in which case such a beam as is shown in Fig. 9 is preferable, with the top B of wood and the sloping side r of 90 steel, carrying the leveler in the rear. The rear sill A, dragging upon the ground, erases all furrows made by the teeth and leaves the ground in a smooth condition for planting or sowing. The teeth a a a may also be attached 95 to the sills A A A, crossing the crowning part of the beams B B B. (See Fig. 10.)

The harrow may also be constructed by attaching the sloping sides r s and the sills A A, Fig. 8, to an ordinary cultivator, or the forward-sloping side and sill may be dispensed with, if desired. The sills A A may also be

bolted high or low on the sloping sides *r s* of the beam *B*, and thereby operate as a gage for raising or lowering the teeth *a a a*.

The harrow is operated by attaching the 5 evener *C* with the chains *ff* to the sills *A A*, to which the horses may be hitched.

Having thus described my invention, what I claim, and desire to secure by Letters Patent, is—

10 1. The graduated springing beams carrying the teeth, with an adjustable sill in front and behind the teeth attached thereto, substantially as set forth and described.

15 2. In harrows, the combination of the beams drooping behind for the purpose of carrying a leveler, with the adjustable rear leveler, and having springs attached to the beams or to

cross-pieces fastened to the beams, substantially as set forth.

3. In harrows, the straight beams with a 20 spring attachment in front and in the rear, with levelers attached thereto, the beams carrying spring-teeth projecting forward, substantially as set forth and described.

4. In harrows, spring arch-beams, with a 25 graduated leveler attached to the front end and to the rear thereof, with teeth attached to the beams by bolts passing through the spring-teeth and beams, substantially as set forth and described.

EFFINGER E. WHIPPLE.
